UNITED STATES PATENT OFFICE.

JOSEPH WARMUTH, OF MINNEAPOLIS, MINNESOTA.

DESIGN FOR A LIGHT FIXTURE.

Application filed March 31, 1922. Serial No. 1,466. Term of patent 14 years.

To all whom it may concern:

Be it known that I, JOSEPH WARMUTH, a citizen of the Republic of Austria, residing at Minneapolis, in the county of Hennepin, and State of Minnesota, have invented a new, original, and ornamental Design for a Light Fixture, of which the following is a specification, reference being had to the accompanying drawing, forming part thereof.

The figure is an elevation of a light fixture, showing my new design.

I claim:

The ornamental design for a light fixture, as shown.

In testimony whereof I affix my signature.

JOSEPH WARMUTH.
